VAN BELL, OF SEVILLE, OHIO.

Letters Patent No. 105,028, dated July 5, 1870.

IMPROVED BED-BOTTOM.

The Schedule referred to in these Letters Patent and making part of the same.

Be it known that I, VAN BELL, of Seville, in the county of Medina and State of Ohio, have invented certain new and useful Improvements in Bed-Bottoms, of which the following is a description.

Like letters of reference refer to like parts in the different views.

This invention relates to a bed-bottom, the same being constructed of thin, narrow strips of wood, interlaced or woven together, and the ends thereof secured in a frame of the same material, as herein described.

This invention will be readily understood from the illustration, fig. 1, in which it will be seen that the bed-bottom consists of thin, narrow strips of wood, interwoven, forming a net-work of slats, A B, the ends thereof being secured between the rails C and cleat D, fig. 2, by means of nails or pins, a, driven therein, as shown in the drawing.

On the under side of the slats, and longitudinally therewith, is a strip, F, also indicated by the dotted lines b, fig. 1.

Said strip is secured to the foot-rails by a wire, c, inclosing the projecting ends thereof. The purpose of said strip is to assist in supporting the superimposed weight of the bed, in the event that the bottom should settle much thereby.

A bed-bottom thus constructed is not only simple in its arrangement and construction, but it is also cheaply made. It is light, strong, and durable, and highly elastic, so that it can be lain on with ease and comfort.

Claim.

What I claim as my improvement, and desire to secure by Letters Patent, is—

The interwoven slats A B, rails C, cleats D, and central strip F, when arranged and combined substantially as described, and for the purpose specified.

VAN BELL.
